UNITED STATES PATENT OFFICE.

HOWARD F. BLEDSOE, OF ELLENSBURG, WASHINGTON.

INNER TUBE.

Application filed January 16, 1922. Serial No. 529,755.

To all whom it may concern:

Be it known that I, HOWARD F. BLEDSOE, a citizen of the United States, residing at Ellensburg, in the county of Kittitas and 5 State of Washington, have invented new and useful Improvements in Inner Tubes, of which the following is a specification.

This invention has for its primary object, the provision of an inner tube for pneumatic 10 tires, and one which is constructed to minimize the possibility of blowouts.

More specifically stated, the invention contemplates strengthening of the tube by the use of cord spirally wound about the tube 15 and also about a non-flexible annulus arranged to engage the inner circumference of the tube to prevent the latter from being expanded to its maximum extent, and to make it possible for the tube to maintain what- 20 ever strain it is subjected to should the latter expand from weakness.

The nature and advantages of the invention will be better understood when the following detailed description is read in connection with the accompanying drawings, 25 the invention residing in the construction, combination, and arrangement of parts as claimed.

In the drawings forming part of this application, like numerals of reference indicate 30 similar parts in the several views, and wherein:

Figure 1 is a side elevation of a tube constructed in accordance with the invention.

Figure 2 is an enlarged fragmentary view 35 of the tube with the outer rubberized covering removed.

Figure 3 is a detail view of the non-flexible annulus.

Figure 4 is an enlarged transverse sectional view.

Referring to the drawings in detail, 10 indicates an inner tube of any wellknown construction which has associated therewith 45 a non-flexible annulus 11, which may be constructed from any suitable material, and

which is arranged to engage the inner periphery or circumference of the tube 10. In addition to the annulus 11, I also make use of cord, the size of the thread being that 50 generally used in the ordinary cord tire fabric, and the cord is wound spirally about the inner tube 10 and the annulus 11, the cord being utilized to strengthen the tube as will be readily understood. This cord is 55 indicated at 12. By winding the cord spirally about the tube, the convolutions do not cross each other, and hence do not cause any friction. The cord is covered with rubber or other suitable material indicated at 60 14. The outer circumference of the tube is determined by the inner diameter, fixed by the non-flexible annulus 11, plus the diameter of the cord windings as illustrated. In addition to strengthening the tube by the 65 cord windings, the non-flexible annulus prevents the tube from being inflated to its maximum degree, and also materially assists the tube in withstanding the strain it might be subjected to should the tire expand from 70 weakness. The construction is such, that the possibility of blow outs is reduced to a minimum.

While it is believed that from the foregoing description, the nature and advantages 75 of the invention will be readily apparent, I desire to have it understood that I do not limit myself to what is herein shown and described, and that such changes may be re-sorted to when desired as fall within the 80 scope of what is claimed.

What I claim is:—

An inner tube of the character described comprising an inner wall of rubber, a cord wound spirally around same, a rigid strip 85 between the cord winding and the inner wall to fix the inner diameter of the tube and determine the outer periphery and an outer covering of fabric.

In testimony whereof I affix my signature. 90

HOWARD F. BLEDSOE.
